United States Patent Office

Des. 212,526
Patented Oct. 29, 1968

212,526

POUR SPOUT

Gary H. Ward, Fremont, Mich., assignor to Gerber Products Company, Fremont, Mich., a corporation of Michigan

Filed Sept. 13, 1967, Ser. No. 8,580

Term of patent 14 years

(Cl. D9—290)

FIG. 1

FIG. 2

FIG. 3

FIG. 4

FIG. 1 is a perspective view of a pour spout showing my new design wherein the upper edge and the cut out are arcuate.

FIG. 2 is a front elevational view thereof.

FIG. 3 is a side elevational view thereof.

FIG. 4 is a front elevational view of a pour spout showing another form of my new design wherein the upper edge and the cut out are defined by angularly intersecting straight lines, as shown.

I claim:

The ornamental design for a pour spout, as shown and described.
